UNITED STATES PATENT OFFICE.

CHARLES C. SPREEN, OF DETROIT, MICHIGAN.

MECHANICAL REFRIGERATION.

Application filed June 3, 1926. Serial No. 113,473.

My invention relates to mechanical refrigeration and particularly to refrigerant expansion units peculiarly adapted for use with domestic mechanical refrigeration apparatus, 5 and the principle object of my invention is to provide a new and improved refrigerant expansion unit of this type. In the drawings accompanying this specification and forming a part of this application I have shown, for 10 purposes of illustration, one form which my invention may assume. In these drawings:

Figure 1 is an end elevation of the embodiment of my invention shown herein,

Figure 2 is a side elevation of the device 15 shown in Figure 1, while

Figure 3 is a section on the lines 3—3 of Figures 1 and 2.

The embodiment of my invention herein shown comprises an expansion drum 11 of the 20 float type provided at its front end with a reduced extension 12, carrying on the end of this extension 12 inlet and outlet shut-off valves 13 and 14 controlling the flow of refrigerant into and from the drum 11, containing means (not shown) for controlling 25 the flow of liquid refrigerant into the drum 11, and comprising also an enlarged section 15 serving as a header from which depend a plurality of looped expansion tubes 16 arranged 30 with both ends of each tube connected to the header 15, with the tubes 16 encircling and supporting a plurality of vertically aligned containers 17 each adapted to receive a receptacle 18 for the production of artificial ice 35 under the action of the refrigerant within the expansion unit, and with the tubes 16 offset at 19 to cause the tubes 16 to diverge from each other in the direction of extent of the header 15 and containers 17 and receptacles 40 18 to thus permit the tubes 16 to subtend along the containers 17 and receptacles 18 a distance greater than the length over which the tubes 16 may be connected to the header 15 whereby, with receptacles 18 of a length 45 greater than the header 15, the usual practice in order to secure greater capacity in the receptacles 18, the refrigeration is extended over the entire extent of the receptacles 18 and the formation of ice in the receptacles 50 18 occurs comparatively uniformly throughout the entire length of the receptacles 18 instead of being almost entirely confined to the center portion of the receptacles as heretofore.

In the embodiment of my invention herein shown I also provide means to increase the 55 heat transfer into the expansion tubes 16, and

particularly to increase the transfer of heat into the expansion tubes 16 from the containers 17 and receptacles 18, this means comprising herein a series of plates 20 corrugated 60 in the vertical direction, alternated with the tubes 16, each secured to each of the adjacent tubes 16, and each comprising a base 21 disposed below the containers 17 and receptacles 18 in operative relation to the horizontal portion 22 of the looped expansion tubes 16, and a pair of wing portions 23 rising from the base portion 21 on either side of the containers 17 and receptacles 18 in operative relation 65 to the vertical portions 24 of the expansion tubes 16, the entire plate 20 preferably contacting throughout with the containers 17 as shown herein.

From the above description it will be obvious to those skilled in the art that I have 70 provided a new and improved expansion unit particularly adapted for use with domestic mechanical refrigeration apparatus. At the same time, it will also be apparent to those skilled in the art that the particular embodiment of my invention herein shown and described may be variously changed and modified without departing from the spirit of my invention or sacrificing the advantages thereof, and it will therefore be understood that 75 the disclosure herein is illustrative only and that my invention is not limited thereto.

I claim:

1. A refrigerant expansion unit comprising header means adapted for connection with refrigerant expansion tubes, a plurality of refrigerant expansion tubes connected at longitudinally spaced intervals to said header means and diverging in the direction of the length of said header means, and a series of 90 corrugated plates having high heat conductivity interposed between said tubes and each engaging at least one of the adjacent tubes.

2. A refrigerant expansion unit comprising header means adapted for connection with looped refrigerant expansion tubes, a plurality of looped refrigerant expansion tubes connected at longitudinally spaced intervals to said header means, and a series of corrugated plates having high heat conductivity 100 interposed between and extending beyond the sides of said looped tubes, and each engaging at least one of the adjacent tubes.

3. A refrigerant expansion unit comprising header means adapted for connection with looped refrigerant expansion tubes, a plurality of looped refrigerant expansion tubes 110

connected at longitudinally spaced intervals to said header means, and a series of corrugated plates having high heat conductivity interposed between and extending beyond the 5 sides of said looped tubes, having recesses to accommodate ice trays, and each engaging at least one of the adjacent tubes.

4. A refrigerant expansion unit comprising header means adapted for connection with 10 looped refrigerant expansion tubes, a plurality of looped refrigerant expansion tubes connected at longitudinally spaced intervals to said header means, and a series of corrugated plates having high heat conductivity 15 interposed between and extending beyond the sides of said looped tubes, having recesses to accommodate sleeves for ice trays, and each engaging at least one of the adjacent tubes, and sleeves for ice trays disposed in said recesses and attached to said plates. 20

5. A refrigerant expansion unit comprising header means adapted for connection with looped refrigerant expansion tubes, a plurality of looped refrigerant expansion tubes 25 connected at longitudinally spaced intervals to said header means, and diverging in the direction of the length of said header means, and a series of corrugated plates having high heat conductivity interposed between and extending beyond the sides of said looped tubes, having recesses to accommodate sleeves for 30 ice trays, and each engaging at least one of the adjacent tubes, and sleeves for ice trays disposed in said recesses and attached to said plates.

6. A refrigerant expansion unit comprising header means adapted for connection with looped refrigerant expansion tubes, a plurality of looped refrigerant expansion tubes connected at longitudinally spaced intervals to said header means and diverging in the direction of the length of said header means, and a series of corrugated plates having high heat conductivity interposed between and extending beyond the sides of said looped tubes, having recesses to accommodate ice trays, and each engaging at least one of the adjacent tubes. 35 40 45

7. A refrigerant expansion unit comprising header means adapted for connection with looped refrigerant expansion tubes, a plurality of looped refrigerant expansion tubes connected at longitudinally spaced intervals to said header means and diverging in the direction of the length of said header means, and a series of corrugated plates having high heat conductivity interposed between and extending beyond the sides of said looped tubes, having recesses to accommodate sleeves for ice trays, and each engaging at least one of the adjacent tubes, and sleeves for ice trays disposed in said recesses and attached to said plates. 50 55 60

In testimony whereof I hereunto affix my signature.

CHARLES C. SPREEN.
